UNITED STATES PATENT OFFICE.

PHARES E. GETZ AND CARL VAUGHN, OF NEOSHO, MISSOURI.

MIST-DAMPENER.

1,261,803.

Specification of Letters Patent. Patented Apr. 9, 1918.

Application filed January 12, 1916. Serial No. 71,760.

To all whom it may concern:

Be it known that we, PHARES E. GETZ and CARL VAUGHN, citizens of the United States, residing at Neosho, in the county of Newton, State of Missouri, have invented a new and useful Mist-Dampener, of which the following is a specification.

The device forming the subject matter of this application is adapted to be employed in a laundry for the purpose of dampening articles which are about to be ironed.

The invention aims to provide a structure of this sort into which the articles to be dampened may be introduced readily, and from which such articles may be removed conveniently after the dampening process has been completed.

A further object of the invention is to provide novel means for producing a spray within the receptacle portion of the dampener, and to provide novel means for controlling the spray.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:

Figure 1 shows the invention in top plan; Fig. 2 is a vertical longitudinal section; Figs. 3 and 4 are fragmental transverse sections, wherein the spray mechanism is disclosed in different positions;

Fig. 5 is a perspective of the bracket which supports the yieldably actuated spray producing means.

In carrying out the present invention there is provided a receptacle 1 of any desired form, the receptacle 1 being open at the top and including a bottom 2, side walls 3 and end walls 4. Extended across one end of the receptacle 1 exteriorly thereof is a water supply pipe 7 provided intermediate its ends with any suitable means indicated at 8 whereby the supply pipe 7 may be connected with a source of water supply. Assembled

with the ends of the pipe 7 are rectangularly disposed pipes 9, constituting arms, the arms passing through the end walls 4 of the receptacle 1. Onto the ends of the arms 9 are threaded caps 10 which bear against one of the end walls 4 as clearly disclosed in Fig. 2. The caps 10 exercise a double function, in that they constitute a means for holding the conduit comprising the pipes 7 and 9 in place and constitute, also, a removable means whereby access may be had to the pipes 9, for the purpose of cleaning these elements out. The receptacle 1 is equipped adjacent its bottom 2 with a drain pipe 5 and supported in the receptacle 1 in spaced relation to the bottom 2 is a false bottom 6 which may be a screen, the false bottom serving to prevent the material being dampened from coming into contact with any water which may lie on the bottom 2 of the receptacle 1, the material which is to be dampened ordinarily being held for a moment within the contour of the receptacle 1 and then being removed therefrom.

A plurality of discharge nozzles 11 enter the arms 9 of the water conduit at intervals, the upper ends 12 of the nozzles upstanding above the lower portions of the parts 9, as clearly indicated in Figs. 3 and 4 so that any sediment which may be traversing the arms or pipes 9, will not find its way readily into the nozzles 11.

Secured to the side walls 3 of the receptacle 1, within the contour of the receptacle, are upper ribs 14. These ribs 14 exercise three functions. First they serve to strengthen the receptacle, secondly, they serve to prevent, to some degree, the water proceeding from the nozzles 11 from spattering out of the receptacle, and thirdly, they prevent the garments from coming into contact with the nozzles 11 and parts therebelow, when the garments are introduced into the receptacle 1.

Disposed within the receptacle 1 and secured to the side walls 3 thereof are lower ribs 15 having upstanding flanges 16. The invention comprises a plurality of sickle-shaped brackets 17, each embodying a depending shank 18, there being one bracket 105 for each of the nozzles 11. The shanks 18 of the brackets 17 are introduced between the flanges 16 of the lower ribs 15 and the side walls 3 of the receptacle 1, the shanks of the brackets thus being housed, so that 110

when the garments are introduced into the receptacle 1, the garments will not be likely to be caught or injured by the shanks of the brackets. A single set of securing elements 5 19 constitutes the means for holding both the brackets 17 and the lower ribs 15 to the side walls 3 of the receptacle 1, the shanks 18 of the brackets being provided with openings 20 adapted to receive the securing elements. In the upper and lower horizontal portions of the brackets 17 are formed openings 21 in which are slidably mounted stems 22 provided at their upper ends with cup-shaped spray heads 23. Nuts 24 are 10 threaded onto the lower ends of the stems 22 and engage the lower ends of the brackets 17. Interposed between the spray heads 23 and the upper portions of the brackets 17 are compression springs 25.

20 In practical operation, water passes through the pipe 7 into the arms 9 and is discharged through the nozzles 11 onto the spray heads 23, the water thus being converted into a fine mist which is projected 25 onto the garments or other articles introduced into the receptacle 1. It is to be observed that the spray heads 23 are yieldably supported by the springs 25. The distance between the spray heads 23 and the lower 30 ends of the nozzles 11, as well as the pressure exerted by the springs 25 may be adjusted by shifting the positions of the nuts 24. When water is discharged through the nozzles 11 under a strong pressure, the compressive effort of the springs 25 is increased 35 accordingly, by a proper manipulation of the nuts 24. The nozzles 11 are bendable, and the brackets 17 are bendable also. One or both of these elements may be bent 40 outwardly, away from the adjacent side wall 3 of the receptacle as shown in Fig. 4, thereby to vary the angle of impact between the water proceeding through the nozzles 11, and the spray head 23, it being possible, by 45 this manipulation of the nozzle 11 or the bracket 17 or both of these elements, to vary the quantity of water discharged, and also to vary the angle at which the water is discharged.

Copies of this patent may be obtained for five cents each, by addressing the "Commissioner of Patents, Washington, D. C."

Having thus described the invention, what 50 is claimed is:—

1. A device for dampening laundry articles, comprising a receptacle embodying a side wall; a downwardly discharging nozzle located adjacent the side wall; means 55 for supplying liquid to the nozzle; a bracket carried by the side wall and located below the nozzle; a spray head coöperating with the nozzle and mounted in the bracket; an inwardly projecting upper rib mounted on 60 the side wall above the nozzle and overhanging the nozzle; and an inwardly projecting lower rib mounted on the side wall below the bracket, the upper rib constituting a deflector for liquid proceeding from 65 the nozzle, and constituting means for protecting the articles to be dampened from contact with the nozzle when the articles are inserted into the receptacle, the lower rib constituting means for protecting the 70 articles from contact with the bracket, when the articles are removed from the receptacle.

2. A device for dampening laundry articles, comprising a receptacle; a sickle-shaped bracket comprising top and bottom members, a connection therebetween, and a shank depending from the bottom member; means for securing the shank to the side wall of the receptacle; a stem 75 slideable in the top and bottom members 80 of the bracket; an adjusting nut on the stem and coöperating with the bottom member of the bracket; a spray head on the upper end of the stem; a compression spring interposed between the spray head 85 and the top member of the bracket; and a nozzle discharging against the spray head, the bracket being bendable adjacent the stem to permit an adjustment of the spray head with respect to the nozzle. 90

In testimony that we claim the foregoing as our own, we have hereto affixed our signatures in the presence of two witnesses.
